[57] CLAIM

The ornamental design for a transmission table top, as shown and described.

DESCRIPTION

FIG. 1 is a top perspective view of a transmission table top showing my new design;

FIG. 2 is a top plan view thereof;

FIG. 3 is a right end elevational view, the left end being a mirror image thereof;

FIG. 4 is a front elevational view, the rear side being a mirror image thereof; and

FIG. 5 is a bottom plan view thereof.

The broken line showing of a table frame is for illustrative purposes only and forms no part of the claimed design.

FIG. 1

FIG. 2

FIG. 3

FIG. 4

FIG. 5
